CLAIM

The ornamental design for a two ply knitted fabric, as shown and described.

DESCRIPTION

FIG. 1 is a top plan view of a two ply knitted fabric, showing my new design;

FIG. 2 is a bottom plan view thereof;

FIG. 3 is an enlarged fragmentary front view of the area within the circled region 3 of FIG. 1; and,

FIG. 4 is an enlarged fragmentary front view of the area within the circled region 4 of FIG. 2.

The fabric has no substantial thickness. The broken lines in the drawing indicate that the knitted fabric has indeterminate length.
